UNITED STATES PATENT OFFICE

2,471,512

BOTTLE HOLDER

Everett W. Barlock, Ann Arbor, Mich., assignor of
one-half to Pearle S. Reimann, Ann Arbor,
Mich.

Application November 18, 1947, Serial No. 786,707

4 Claims. (Cl. 248—102)

1

The present invention relates to a novel and improved small bottle holder which is adapted to accommodate and retain in position a bottle containing a finger nail preparation such as polish, cleaner or the like.

An object of the invention is to provide a bottle holder which is characterized by two essential units, a relatively fixed stand and a complementary bottle grip and holder which is cradled for pendulous rocking in said stand, whereby when the bottle is placed in said second unit and the closure is removed, the contents is available for convenient and handy use.

It is another object of the invention to prevent spilling of nail polish when the same is dispensed while holding the bottle in one's hand. Often when the contents of the bottle is diminished it is a practice to hold the bottle in the hand and to thus render the contents more available to the insertible and removable brush. Experience has shown, however, that polishing one's nails is often a tedious job and unless some satisfactory means is provided to adequately hold the bottle against tippling, disastrous results are often encountered. So, the primary object of the invention is, as before indicated, to provide a simple and practical holder which will not only steady and anchor the bottle but will allow same to be tilted with ease for safe and adaptable results.

More specifically, in reducing to practice a preferred embodiment of the invention I provide a simple base or stand which is anchorable on a table or the like, said stand being such as to accommodate the swingably mounted bottle holder and the latter being cradled in the stand in a manner to normally retain the bottle in a perpendicular or upright position but to allow same to be tilted back or forth for accessibility purposes.

Other objects and advantages of the invention will become more readily apparent from the following description and accompanying illustrative drawing.

In the drawing:

Figure 1 is a side elevational view of a bottle holder constructed in accordance with this invention and showing the manner in which same is constructed and used;

Figure 2 is a view at right angles to Figure 1, the parts being in section and the view being a central vertical section;

Figure 3 is a top plan view of the structure seen in Figure 2, the bottle being omitted;

2

Figure 4 is a horizontal section on the line 4—4 of Figure 2, looking in the direction of the arrows; and,

Figure 5 is an enlarged perspective view of one of the parts.

Reference is now had to the drawing by distinguishing reference numerals and, noting Figure 1 it will be seen that the unit or part of the assemblage which I call the stand comprises 10 a suction cup 6 forming a conveniently anchorable base. This serves to accommodate and support a substantially U-shaped standard or upright 7, the latter being detachably and adjustably mounted on the base as illustrated in 15 Figure 2. Reference being had to the latter figure it will be seen that the suction cup is frusto-conical and that the flattened top or crown portion 8 serves to accommodate a bolt 9 and washer 10 which parts in turn serve to accommodate the L-shaped members which go to 20 make up the stated U-shaped standard. Each L-shaped member comprises a vertically disposable upright 11 and a horizontally disposable inturned attaching portion 12. The portions 12 25 overlap and are slotted, as at 13, to accommodate the bolt and nut means. It follows that by locating the uprights in parallelism and the inturned slotted portions in overlapping relation a U-shaped stand, attached to a suction cup, is 30 had, the parts of said stand being shiftable toward and from each other to increase or decrease the width of said stand.

The nail polish or equivalent bottle is denoted by the numeral 14 and this has a removable 35 closure 15, said bottle being adapted to be placed, for use in the holder unit 16. The latter unit is such as to accommodate the bottle and is pivoted as at 17 between the uprights, thus providing the desired cradling and tilting action.

40 The unit 16 is actually made up of four L-shaped members, these being arranged in pairs, the members of each pair being opposed, and the respective pairs being at right angles to each other as is clear from the drawing. The 45 members 18 of one pair have inturned slotted portions 19 which are overlapped and assembled by the bolt 20. The corresponding members 21 of the remaining pair have laterally inturned and slotted portions 22 and these are also overlapped 50 and underlie the overlapping end portions 19 and are secured by the same bolt 20. Thus, the members are all L-shaped and have their short limbs or laterally directed slotted portions properly overlapped and adjustably bolted together. 55 This makes it possible to increase or decrease

the size of the cradle to accommodate small bottles of varying sizes. It also makes it possible to adjust the cradle to fit the stand or vice versa.

Reviewing the structure in terms of generalities it will be seen that it is characterized by a base in the form of rubber or equivalent suction cup attached to a table or the like, said base carrying a U-shaped stand and said stand being made up of L-shaped members adjustably bolted to the base. The cradle is likewise made up of four L-shaped members adjustably bolted and assembled with two of these members hinged between the members which go to make up the stand. This makes it possible to take six L-shaped members and to use simple washers and bolts in the rubber suction cup and thus produce the structure wanted.

A careful consideration of the foregoing description in conjunction with the invention as illustrated in the drawing will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

Having described the invention, what is claimed as new is:

1. In a bottle holder of the class described, a relatively stationary stand, a suction cup on said stand for attaching same to the surface of a table or the like, a receiver-type bottle holder, said bottle holder being situated in and tiltably mounted on said stand, the stand being made up of relatively adjustable parts, and said holder also being made up of adjustable parts and the

respective parts of the stand and bottle holder being simultaneously adjustable to handle bottles of varying sizes.

2. A tilttable bottle holder of the class described comprising a base adapted to sit on a table or the like, a U-shaped standard attached to said base, and a bottle gripping receiver-type holder, said holder being cradled for tilting in said stand, the stand being made up of adjustably connected L-shaped members.

3. A tilttable bottle holder of the class described comprising a base adapted to sit on a table or the like, a U-shaped standard attached to said base, and a bottle gripping receiver-type holder, said holder being cradled for tilting in said stand, the stand being made up of adjustably connected L-shaped members, and said holder being also made of adjustably connected L-shaped members.

4. In a structure of the class described a suction cap, a pair of L-shaped members having their short limbs slotted and adjustably bolted to said suction cup, and a bottle holder cradled in said stand between said L-shaped members.
